HOT AIR BLOWER FOR HAIRDRYING APPARATUS

Lawrie G. McIntosh, Weston, Ontario, Canada, assignor to Rotor Electric Company Limited, Rexdale, Ontario, Canada

Filed July 6, 1961, Ser. No. 65,828

Term of patent 14 years

(Cl. D86—10)

FIG. 1

FIG. 2

FIGURE 1 is a perspective view of a hot air blower for hairdressing apparatus, showing my new design; and FIGURE 2 is a sectional view taken along line 2—2 in FIGURE 1.

The underside of the hot air blower shown in FIGURES 1 and 2 is in the shape of a circular plate.

I claim:

The ornamental design for a hot air blower for hairdressing apparatus, as shown and described.
